UNITED STATES PATENT OFFICE.

STANLEY T. HARVEY, OF VANCOUVER, BRITISH COLUMBIA, CANADA.

ADVERTISING DISPLAY DEVICE.

1,337,315.

Specification of Letters Patent. Patented Apr. 20, 1920.

Application filed June 2, 1919. Serial No. 301,303.

To all whom it may concern:

Be it known that I, STANLEY T. HARVEY, a citizen of the Dominion of Canada, residing at Vancouver, in the Province of British Columbia, Canada, have invented certain new and useful Improvements in Advertising Display Devices, of which the following is a specification.

This invention relates to an advertising device of that class wherein a series of slideable panels carrying display advertisements are laterally movable in front of and behind a corresponding series of fixed display advertisements, whereby periodic exposure of the fixed and movable advertisements is successively effected.

The object of the invention is to obtain a maximum of advertisement exposure with a mechanism that is simple to construct and 20 is economical in the motor power used.

The invention is particularly described in the following specification, reference being made to the drawings by which it is accompanied, in which:

25 Figure 1 is a front view of the device in perspective.

Fig. 2, a horizontal plan on the line 2—2 in Fig. 1.

Fig. 3 is a detail of the chain in plan 30 showing the driving pin.

Fig. 4 is a detail section of the movable panel showing its track support and chain drive connection.

Fig. 5 is an elevation of the same from the 35 back, and

Fig. 6 is a view of the back of the frame showing the arrangement of the chain drive by which the movable panels are operated.

The framework comprises two side posts 40 or styles 2 between which extend top and bottom cross rails 3 and 4 and intermediate cross rails 5, dividing the framework into three horizontally disposed spaces.

The underside of the cross rail 3, the top 45 of the bottom rail 4, and the top and bottom of each intermediate rail 5, are lengthwise grooved as at 6, to receive movable panels 8, which fit in the grooves of the cross rails and have small grooved wheels 9 adjacent 50 each end to run on the edge of a rail 10, see Figs. 4 and 5, inserted along the middle of the top groove 6 of each cross rail 5 and 4. The length of these movable panels is approximately two-thirds of the length of the 55 horizontally disposed spaces between the side posts 2.

Down the front of the frame 2, 3, 4, 5, is secured a middle panel 7, the width of which is approximately one-third the space between the side posts, and behind the plane 60 of the grooves 6 fixed panels 11 are inserted which extend from each side post 2 to a position in line with the adjacent edge of the middle panel 7.

On the faces of the middle panel 7, both 65 halves of the movable panels 8 and the fixed side panels 11, are display advertisements. Those on the middle panel 7 are constantly exposed, while those on the faces of the stationary panels 11 and movable panels 8 are 70 alternately revealed and hidden as the panels 8 are moved from the one side to the other.

The movable panels 8 are disposed alternately to opposite sides of the frame and 75 are periodically moved endwise by a flexible endless chain 12, preferably a sprocket chain, which passes from a sprocket 26 driven at a moderately slow speed from a motor or other suitable source of power, not shown, 80 behind the panels and within the frame 2, 3, 4, 5. This endless chain 12 passes around small sheaves 13, 14, 15, 16, 17, 18, 19, 20, 21, 22, 23, 24, 25, mounted in the cross rails 5 and such supplementary framing as may be 85 necessary behind and in planes parallel to the face of the sign. This chain 12 has in one place a pin 27 projecting from each side of it, which engages the sides of a double forked projection 28 secured to each panel 90 8, by which the panels are carried successively from side to side of the frame.

The small sheaves around which the chain passes are arranged somewhat as shown, those 14, 15, 16, 17, 18 being in one plane to 95 engage the inner fork of each panel projection 28, and those 21, 22, 23, 24, 25, and the sprocket 26 are in an adjacent parallel plane to engage the outer fork of 28; 13 and 26 being intermediate guide pulleys.

100 The forked projections 28 are secured to approximately the midlength of each slideable panel 8 adjacent the bottom edge of the top panel, the mid-depth of the middle panel and the upper edge of the lower panel respectively.

105 The small sheaves 15, 17, 19, 22, 24 and the sprocket wheel 26 are in line with the edges of the front panel 7, (see Fig. 6) that is, corresponding to the projections 28 in the middle of the movable panels, when those panels are at the limit of their movement to

that side, so that the pin 27 of the chain 12 will freely leave its engagement with the fork member 28 as soon as the panel has been moved to its limit.

5 The other sheaves 14, 16, 18, 21, 23, 25 are a sufficient distance outside the edges of the middle panels 7 to insure that the projecting pin 27 of the chain 12 will engage the forked projections 28 of the movable panels.

10 As stated, the shaft on which the driving sprocket 26 is secured may be driven by any suitable means from any convenient source of power, preferably by a small electric motor, conveniently placed within the 15 framework of the sign, the speed of which motor is reduced to that required.

The power required is very light as only one panel is moved at a time, and being mounted on wheels they require but a trifling amount of power to travel them 20 from side to side.

Although a sprocket chain is used and has proven satisfactory, a flexible endless line of any kind will effect the desired object provided the panel engaging projection of the 25 line, corresponding to the pin 27, be such that twist of the line will not prevent its proper engagement with the forked projection 28 of the movable panels.

30 With this construction as described and illustrated, a large amount of advertising space is rendered available, an amount equivalent to two-thirds in excess of the area inclosed by the sign frame. Of this 35 available area four-thirds, comprising the fixed surfaces 11 and the movable surfaces 8, has the advantage of continual change, and two-thirds, comprising the movable panels 8, of change and motion, while the 40 remaining one-third, the front middle panel 7, which alone is unchangeable, derives advantage from its proximity to the changeable and moving areas.

45 While one panel is in motion the others are at rest providing full opportunity for inspection of the advertising matter revealed.

The sign is capable of considerable variation in its application, from the smaller 50 sizes adaptable to window display to the largest size of sign used. The sign may be double faced, that the same mechanism may operate at both sides.

55 In operation, assuming the upper and the lower movable panels 8 in Fig. 1 to be on the left of their runway, and the intermediate panel 8 to be on the right, the projecting pin 27 of the chain 12 as it passes over the sheave 14 will engage the inner fork of 60 the projection 28 of that panel and will carry the panel across to the right, where at the limit of its movement the chain 12 and its pin 27 will turn downward over the sheave 15 and around the sheave 16 where 65 the pin 27 will encounter the inner fork of

the projection 28 of the next movable panel below and will carry it to the left. Turning downward over the sheave 17, it will leave that panel on the left and passing around the sheave 18 will engage the inner fork of 70 the projection 28 of the bottom panel and will carry it to the right, disengaging from the projection as the chain passes upward around the sheave 19. All the panels 8 have thus been moved across to their opposite 75 side.

The chain 12, as it passes over the sheave 19 to the sheave 21 over the intermediate sheave 20, is diverted from the plane of the inner fork of the projection 28 to that of the 80 outer fork, and as the projecting pin 27 of the chain passes around the sheave 21 it engages the outer fork of the projection 28 of the upper panel and moves it from right to left disengaging from it as it passes downward over the sheave 22. As it passes around the sheave 23 it will engage the outer fork of the next panel below and will move it from left to right, disengaging from its projection 28 as it passes downward over 85 the sheave 24, and passing around the sheave 25 the pin 27 will engage the outer fork of the projection 28 of the bottom panel and move it from right to left, disengaging from it as it passes around the sprocket 26 from 90 which the chain derives its movement. This completes the cycle of movement, all the panels 8 having been moved across to the other side and back.

Care must be taken in arranging the position of the sheaves 15, 17, 19, 22, 24 and the driving sprocket 26 that the pin 27 of the sprocket chain will free itself from engagement with the forked projection 28 of each panel as that panel reaches the limit of its 105 movement.

Having now particularly described my invention, I hereby declare that what I claim as new and desire to be protected in by Letters Patent, is:

1. An advertising device, comprising the combination with a suitable frame supporting fixed display surfaces in adjacent parallel planes, the adjacent edges of which surfaces are in line with one another, cross rails between these vertically disposed surfaces dividing them into horizontally disposed groups, a panel endwise movable along the cross rails between the surfaces of each group, and means for successively moving the panels of adjacent groups in opposite directions whereby the display surfaces of the movable panels and of the surfaces which they move in front of, are alternately hidden and revealed.

2. An advertising device comprising, the combination with a suitable frame supporting three vertically disposed display surfaces in adjacent parallel planes, the middle one being in front of the two side ones with

- the adjacent edges in line with one another, cross rails between these vertically disposed surfaces dividing them into horizontally disposed groups, a panel mounted to move 5 along each group between the surfaces, the length of each movable panel being approximately equal to twice the width of the vertically disposed surfaces, and means for successively moving each panel from one 10 side to the other to project that end of each that was behind the middle front surface in front of the exposed face of the side one behind and to reveal the surface of the other side.
- 15 3. An advertising device, comprising the combination with a suitable frame supporting three vertically disposed display surfaces in adjacent parallel planes, the middle one being in front of the two side ones with 20 the adjacent edges in line with one another, cross rails between these vertically disposed surfaces dividing them into horizontally disposed groups, a panel mounted to move along each group between the surfaces, the 25 length of each panel extending across the width of one of the side display surfaces to the opposite edge of the middle surface, and means for successively moving the slidable panels of the adjacent groups in opposite 30 directions.
4. An advertising device, comprising the combination with a suitable frame supporting three vertically disposed display surfaces in adjacent parallel planes, the middle 35 one being in front of the two side ones with the adjacent edges in line with one another, cross rails between these vertically disposed surfaces dividing them into horizontally disposed groups, a panel mounted to move 40 along each group between the surfaces, the length of said panel extending across the width of one of the side display surfaces to the opposite edge of the middle display surface, and an endless flexible line traveling 45 over sheaves, said line having an enlargement that will engage a projection from each of the movable panels and move them successively from side to side.
5. An advertising device, comprising the 50 combination with a suitable frame supporting three vertically disposed surfaces in adjacent parallel planes, the middle one being in front of the two side ones, cross rails between these vertically disposed surfaces di- 55 viding them into horizontally disposed groups, a panel slidably mounted to move in grooves of the cross rails along each group,
- the length of the panel extending across the width of one of the side display surfaces to the opposite edge of the middle one, an endless sprocket chain traveling over grooved 60 sheaves disposed on each side of the middle surface to carry the chain parallel with the cross rails to move in opposite directions in adjacent groups, said chain having a projection to engage a corresponding projection from each panel, and a sprocket wheel for moving the chain. 65
6. An advertising device, comprising the combination with a suitable frame supporting three vertically disposed display surfaces in adjacent parallel planes, the middle surface being in front of the two side ones, cross rails between these vertically disposed 70 surfaces dividing them into horizontally disposed groups, the adjacent edges of each cross rail being grooved, panels endwise movable on roller wheels in the grooves of the cross rails along each group, the length of each panel extending across one of the 75 side surfaces to the further edge of the middle surface, an endless chain passing around sheaves mounted adjacent the vertical edges of the middle surface to move parallel with the cross rails in opposite directions in adjacent groups, said chain having a pin projecting from each side to engage a corresponding projection in each movable panel, and means for endwise moving the chain. 80
7. In an advertising device, the combination with a suitable frame supporting fixed display surfaces in adjacent parallel planes, said frame including a top and a bottom cross rail, a panel endwise movable along the cross rails and of a length to extend 90 over approximately two-thirds of the display surfaces, means for successively moving the panel back and forth endwise whereby to first expose one section of the panel and one of the fixed display surfaces and 95 then expose another section of the panel and another of the fixed display surfaces accordingly as the panel is moved in one direction or the other, said moving means comprising a single flexible line passing 100 over sheaves and moving unidirectionally with provisions for engaging said movable panel to automatically move it first in one direction and then in the opposite direction 105 substantially as shown and for the purpose 110 described.

In testimony whereof I affix my signature.

STANLEY T. HARVEY.
